UNITED STATES PATENT OFFICE.

ROBERT O. BATLEY, OF KANSAS CITY, MISSOURI.

WINDOW-PLATFORM.

1,259,342.

Specification of Letters Patent. Patented Mar. 12, 1918.

Application filed July 4, 1917. Serial No. 179,060.

To all whom it may concern:

Be it known that I, ROBERT O. BATLEY, a citizen of the United States, residing at Kansas City, in the county of Jackson and 5 State of Missouri, have invented certain new and useful Improvements in Window-Platforms, of which the following is a specification.

This invention relates to window platforms of that class designed to afford a safe support for anyone desiring to perform work on or at the outer side of a window, and my object is to provide a device of this 10 character of very light, compact, strong, durable and cheap construction, which can be easily and quickly placed in or removed 15 from position, and which is adjustable to accommodate window casings of different widths.

More specifically my object is to produce a 20 platform equipped with anchor hooks to limit outward movement, parts to support the platform member and provided with shoulders for applying inward thrust 25 against the window casing, and inclined flexible connections between the outer end of the platform and the said parts; said flexible connections in conjunction with the platform and the shouldered parts, constituting a truss member for resisting downward 30 movement of the outer end of the platform member.

With the objects named in view the invention consists in certain novel and peculiar 35 features of construction and organization of parts as hereinafter described and claimed, and in order that it may be more fully understood reference is to be had to the accompanying drawing, in which:

Figure 1, is a top plan view of a window platform embodying my invention, and shown as applied in operative relation to a window casing.

Fig. 2, is a side view of the platform, the 45 casing being shown in section.

In the said drawing, 1 indicates the lower portion of a window casing, 2 the sill strip and 3 the drain strip thereof. 4 is a platform bridging the space between and secured 50 to a pair of bars 5, preferably of wood, and secured to and projecting inwardly from the bars 5 are metal arms 6, said arms being provided with longitudinal slots 7 through which the securing bolts 8 extend, nuts 9 engaging said bolts and clamping the arms 6 and bars 5 rigidly together at the desired

point of adjustment, said parts when so clamped together constituting a single part, and the front ends of the bars 5 have shoulders 10 for bearing against the outer edge 60 of the drain strip 3. Inwardly of said shoulders arms 6 are bent to form raised arches 11 for extending over the sill strip 2, the inner ends of the arched portions terminating in hooks 12 for engaging around 65 the inner edge of the sill strip.

To form a support for the outer end of the platform, and relieve the arms 6 largely of supporting the platform in a horizontal position, inclined tie strips 13 are secured at 70 their opposite ends around the outer portion of the platform and at their inner ends to the crest portion of the arches 11, the arrangement being such that the weight on the platform shall apply tensional strains 75 on the strip 13 and thus largely remove bending strains from the arms 6, the said strips 13 in conjunction with the bars 5 and arms 6 constituting truss braces of light weight and great strength.

The strips 13 are secured to the outer end of the platform and the ends of bars 5 preferably by bending them around said parts and securing them thereto by screws 14. At their inner ends the strips are secured to the arched portions of arms 6 by bolts 15 and nuts 16, the inner ends of the strips being provided with longitudinal slots 17 to provide for adjustment in conjunction with the slots of arms 6, in accommodating the device to window casings of different width, and in order to guard against accidental slippage of the strips on the arms 6, the upper surfaces of the latter are preferably transversely corrugated as at 18, for engagement by corrugated plates 19 riveted to the strips 13, the slots of said strips of course extending through said plates 19. Furthermore to accommodate adjustment between the arms 6 and strips 13, without bending the latter, the arched portions of the arms where the same are corrugated, are disposed in an inclined plane parallel to that occupied by the strips. It will thus be seen that the 95 distance between the anchoring hooks 12 and the shoulder 10 may be increased or diminished without necessitating the bending and therefore weakening of the strips 13 so that the full tensional strength of the 105 same shall be available in supporting the 110 platform.

110

The method of placing the window platform in or removing it from position is obvious from an inspection of the drawing, and it will be apparent that when a person 5 is standing upon the platform, the slight downward spring of the latter will cause the shoulders 10 to bear heavily against strip 3 or its equivalent, and that the greater portion of the weight will be applied inwardly on said strip 3 and outwardly on the sill. The tensile strain on 10 the strip 13 practically removes from the arms 6, all downward pressure.

From the above description it will be apparent that I have produced an extremely simple, compact, light and inexpensive window platform possessing great strength and rigidity and which is readily adjustable to accommodate window casings of different 20 width, and it is to be understood that I reserve the right to make such changes as properly fall within the spirit and scope of the appended claims.

I claim:

25 1. A window platform comprising a platform proper, bars secured to and projecting inwardly from the platform, the inner ends of the bars constituting shoulders, metal arms secured to the bars and projecting inwardly therefrom and provided 30 with arched portions to extend over the sill of a window and equipped at their in-

ner ends with depending outwardly-facing hooks, and flexible members extending upwardly and inwardly from the outer edge 35 of the platform to the arched portions of the respective arms, and secured at their opposite ends to and serving as a support for the outer portion of said platform.

2. A window platform comprising a platform proper, bars secured to and projecting inwardly from the platform, the inner ends of the bars constituting shoulders, metal arms secured to the bars and projecting inwardly therefrom and provided with 40 arched portions to extend over the sill of a window and equipped at their inner ends with depending outwardly-facing hooks; the outer ends of said arms having longitudinal slots to accommodate adjustment of 45 said hooks toward and from the platform, and flexible connections secured at their outer ends to the platform and extending upwardly and inwardly therefrom to the arched portions of said arms and provided 50 with longitudinal slots, bolts extending through said slots and said arms, and clamping nuts engaging said bolts to clamp 55 said flexible connections rigidly upon said arms.

60 In testimony whereof, I affix my signature.

ROBERT O. BATLEY.
